[57] CLAIM

The ornamental design for a ski rope reel or the like, as shown and described.

DESCRIPTION

FIG. 1 is a perspective view of a ski rope reel or the like showing my new design;

FIG. 2 is a top plan view thereof on a reduced scale;

FIG. 3 is a side elevational view thereof on a reduced scale;

FIG. 4 is a right end elevational view thereof on a reduced scale;

FIG. 5 is a side elevational view thereof opposite that shown in FIG. 3 on a reduced scale;

FIG. 6 is a left end elevational view thereof on a reduced scale;

FIG. 7 is a bottom plan view thereof on a reduced scale.

FIG. 1
